UNITED STATES PATENT OFFICE.

CHRISTOPHER PEARSON, OF PHILADELPHIA, PENNSYLVANIA.

SHOCK-ABSORBING DEVICE FOR GUNS.

1,305,617.

Specification of Letters Patent. Patented June 3, 1919.

Application filed December 17, 1918. Serial No. 267,115.

To all whom it may concern:

Be it known that I, CHRISTOPHER PEARSON, a subject of the King of Great Britain, residing at Philadelphia, in the county of 5 Philadelphia and State of Pennsylvania, have invented certain new and useful Improvements in Shock-Absorbing Devices for Guns, of which the following is a specification.

10 One object of my invention is to provide a shock absorbing device which can be applied to the butt ends of rifles and guns, and which will compensate for the shock caused by the discharge of the gun.

15 Another object is to so construct my improved device that it will in no way interfere with the manipulation of the gun either during the shooting of the gun or when the gun is being used for drill purposes; it being 20 well known that in various exercises during the drill the gun must be dropped upon the ground.

25 A still further object of my invention is to make my improved device of a simple and durable construction and so that it can be readily taken apart for cleaning or repair purposes.

30 These objects, and other advantageous ends which will be described hereinafter, I attain in the following manner, reference being had to the accompanying drawings in which—

35 Figure 1 is a top plan view showing the butt end of a gun with my improved device illustrated in connection therewith, and

Fig. 2 is a sectional elevation taken on the line 2—2 of Fig. 1.

Referring to the drawing, 3 represents the 40 butt end of a gun which is preferably made of wood. Two cylindrical cavities 4 and 5 extend into the butt end 3 from the surface 6. These cavities 4 and 5 are lined with metallic bushings 7. Two plungers 8 and 9 fit within the bushings 7 and coiled springs 45 10 are interposed between the inner ends of the plungers 8 and 9 and the inner ends of the cavities 4 and 5.

50 A sleeve or band 11 surrounds the extreme end portion of the butt 3, as clearly shown in Fig. 2, and a cap 12 slidably fits the sleeve 11. The cap 12 is closed at its outer end 13 and a space 14 is normally provided between the cap end 13 and the surface 6 of the butt

3. The cap 12 has oppositely disposed longitudinally extending slots 15 and the sleeve 55 11 has holes 16 of less length than the slots 15. The holes 16 are normally in alinement with the respective slots 15 and resilient hooks 17, which are secured by screws 18 to the butt 3, have heads 19 adapted to pass 60 through the respective holes 16 and slots 15, so as to prevent the cap from sliding entirely off of the sleeve 11.

The butt 3 is provided with cavities 20 in which the hooks 17 are mounted, said hooks 65 being also provided with finger engaging lugs 21 whereby the hooks 17 can be pressed into the cavities 20 to free the heads 19 from the slots 15, when it is desired to remove the cap. 70

In the use of my invention, the cap 12 serves as a shoulder engaging member and when the gun is fired, the butt end 3 will move toward the closed end 13 of the cap 12, the springs 10 being compressed to take up 75 the shock. The slots 15 permit this relative movement between the butt 3 and the cap 12 and the latter will not become loose during the discharge or manipulation of the gun.

While I have described my invention as 80 taking a particular form, it will be understood that the various parts of my invention may be changed without departing from the spirit thereof, and hence I do not limit myself to the precise construction set forth; but 85 consider that I am at liberty to make such changes and alterations as fairly come within the scope of the appended claims.

Having thus described my invention, what I claim as new and desire to secure by Letters Patent is:

1. A gun having a resiliently pressed shoulder engaging cap slidably mounted on the butt thereof and having slots therein; and resilient hooks secured to said butt and 95 having heads adapted to project outwardly from said butt into said slots, said butt being recessed to permit the hooks to be depressed from said slots when it is desired to remove said cap; substantially as described. 100

2. A gun having a resiliently pressed shoulder engaging cap slidably mounted on the butt thereof and having slots therein; resilient hooks secured to said butt and having heads adapted to project into said slots; 105 said hooks being compressible to withdraw

the heads from said slots; and a sleeve interposed between said butt and the cap and upon which the cap is adapted to slide; said sleeve being secured to the butt and having 5 holes in register with said slots to permit said heads to pass therethrough; substantially as described.

In testimony whereof I have signed my name to this specification in the presence of two subscribing witnesses.

CHRISTOPHER PEARSON.

Witnesses:
